ATTORNEY

UNITED STATES PATENT OFFICE.

GEORGE E. NERNEY, OF ATTLEBORO, MASSACHUSETTS, ASSIGNOR TO BAY STATE OPTICAL COMPANY, A CORPORATION OF MAINE.

DISPLAY-STAND.

1,355,349.

Specification of Letters Patent. Patented Oct. 12, 1920.

Application filed April 23, 1920. Serial No. 375,961.

To all whom it may concern:

Be it known that I, GEORGE E. NERNEY, a citizen of the United States, residing at Attleboro, in the county of Bristol and State 5 of Massachusetts, have invented certain new and useful Improvements in Display-Stands, of which the following is a specification.

My invention relates to devices for holding and displaying articles of various kinds 10 including eyeglasses and spectacles.

The essential objects of my invention are compactness, portability, collapsibility, simplicity of construction and operation, and inexpensiveness.

15 To the enumerated ends essentially my invention consists of such parts and such combinations of parts as fall within the scope of the appended claims.

In the accompanying drawings which 20 form a part of this specification

Figure 1 is a plan view of the blank from which my display stand is formed,

Figs. 2 and 3, front and end elevations respectively of the stand showing a pair of 25 eyeglasses mounted thereon, and

Fig. 4, a section of the stand only taken on line 4—4 of Fig. 2.

Like reference characters indicate like parts throughout the views.

30 To form the stand I employ a substantially rectangular oblong blank 6 cut from a sheet of cardboard or thick paper as shown in Fig. 1, which is next transversely creased at intervals, as at 7, 8, 9 and 10, dividing 35 the blank into areas 12, 13, 14, 15 and 16 respectively. The area 12 is provided with parallel oblong slots 18 spaced from each other longitudinally of the blank. The opposite portion of the blank is cut away, as 40 at 19, to form oppositely disposed inwardly directed fingers comprising the areas 16 extending from the areas 15.

The blank is folded along the enumerated creases to form the structure shown in Figs. 45 2 to 4 inclusive. This consists of an inclined oblong display wall 12 with its lower portion supported on the forward edge of a base 13 from whose rear edge rises an upwardly inclined brace 14. The upper edge 50 of the brace supports depending flaps 15 whose faces coincide with the back face of the portion 12. These inclined flaps or supports carry upon their adjacent lateral edges

the flat fingers 16 which pass loosely through the slots 18, and form upwardly directed 55 supports.

After the described bending or folding, which is easily and manually performed, any article may be placed in the depressed portions 19^x of the fingers to rest against the 60 inclined face or wall 12. In this instance a pair of eyeglasses 20 are so shown.

For transport the parts of the stand may be disengaged from each other and remain as shown in Fig. 1, or may be folded into 65 a flat package along the creases 7, 8, and 9.

Attention is called to a most important function of the device in the clamping or locking of the article between the finger and the resilient display wall. This has been 70 found to be a most efficient practical way of supporting spectacle frames.

I claim:—

1. A display stand comprising a base, a display wall upon the forward portion of 75 said base provided with a slot, a brace upon the rear portion of the base with a depending flap engaging the rear face of the display wall at the upper end thereof, and a finger supported by the flap and projecting 80 through said slot from the lower end of said flap to form a support for an article.

2. As a new article of manufacture, a blank for a display stand comprising an oblong substantially rectangular body provided near one end with parallel spaced longitudinally disposed slots, and having three spaced transversely disposed creases, and provided with a cut away portion near its other end, and having oppositely disposed 90 inwardly curved extensions projecting into the cut away portion provided with creases adjacent the extensions.

3. A display stand formed of a single piece of material and comprising a base, an 95 inclined display wall, an oppositely inclined brace with separated flap extensions engaging opposite side portions of the rear face of the display wall, the said display wall having slots, and the said flaps having fingers 100 on their adjacent lateral edges extended through said slots and having depressions upon their upper edges.

In testimony whereof I have affixed my signature.

GEORGE E. NERNEY,
